UNITED STATES PATENT OFFICE

WILLIAM L. COOPER, OF KANKAKEE, ILLINOIS, ASSIGNOR TO FLORENCE STOVE COMPANY, OF BOSTON, MASSACHUSETTS, A CORPORATION

OIL HEATING STOVE

Application filed November 18, 1929. Serial No. 407,923.

This invention relates in general to stoves and has more particular reference to a novel stove construction adaptable to stoves employing a fluid fuel for heating.

The present invention contemplates the provisions of a novel fluid fuel stove in which the fluid container is concealed from view, protected against accidental damage, insulated from the heat produced in the use of the stove, and slidably supported in the stove to permit its removal for refilling or partial removal for ascertaining the amount of fuel contained in the tank or container.

A primary object of this invention is therefore to provide such a fluid fuel stove with means for slidably receiving and concealing a fuel tank or container.

An important object of the invention is the provision of a fuel tank for such a stove which will be insulated from the heat produced in the use of the stove and which may be concealed in a pocket or compartment formed within the burner portion of the stove.

Another important object of the invention is the provision of a fluid fuel stove having a usual burner portion and having a pocket or compartment formed in the burner portion to slidably receive a novel fuel tank which will be guided into its proper operating position and which will close an end of the recess or compartment.

Other objects and advantages of the invention will be apparent as it is better understood from the following description which with the accompanying drawings disclose a preferred embodiment thereof.

The drawings

Fig. 1 is a perspective view of a stove embodying the principles of the invention;

Fig. 2 is a section taken substantially on the line 2—2 of Fig. 1;

Fig. 3 is a section taken substantially on the line 3—3 of Fig. 2;

Fig. 4 is a fragmentary plan view of the stove shown in Fig. 1 partially exposing the fuel container tank; and

Fig. 5 is a side view of the fuel tank showing the tank removed from the stove and in a position to be refilled or refueled.

For the purpose of illustrating the invention, the drawings show a fluid fuel stove having a body or burner portion 11 which comprises a front side 12, a back 13 and side walls 14 constructed about a suitable frame 15, the whole structure being supported in any suitable manner or as shown in Fig. 1 by legs 16. It will be understood that the burner portion 11 forms an enclosure about a plurality of burners, not shown, which are controlled by handles 17 projecting from the front of the stove, the burners being adapted to direct heat to a plurality of grids or plates 18 supported in a usual manner in a top frame member 19 of the burner portion 11 for supporting cooking utensils which are used to hold food being cooked.

A plate 20 underlies each of the rear grids 18, in the form illustrated in Fig. 3, which will guide the heating gases thereto and maintain the gases in spaced relation to the underlying fuel tank or container.

An aperture 21 is provided in one of the walls 14 and adapted to communicate with a pocket or compartment 22 formed within the burner portion 11 for a purpose which will be more fully described presently. The pocket 22 is formed by a plate having a top horizontal portion 23 and vertical sides 24 and 25 cooperating with one of the sides 14 and the back 13 of the burner portion and being held in place by bolt and nut assemblies 26 passing through a depending marginal portion 27 at the inner side of the top frame 19 and a vertical flange 28 extending about the front end and a side of the pocket 22 above the horizontal top 23; the top 23 and the sides 24 and 25 of this plate separate the pocket 22 from the remainder of the burner portion 11 and provide means for protecting and concealing a fuel tank 29 which will be more fully described hereinafter. To supplement the heat baffling means provided by the top 23 and sides 24 and 25, an angular plate having a top 31 and a side 32 is mounted in spaced relation with the top 23 and the side 25 respectively of the heat baffling means by any suitable means such as spot welded depressed lugs, shown at 33 in Figs. 2 and 3, and pro-

viding an air space 34 between the two plates to insulate the pocket 22 from the influence of the heat produced in the use of the stove.

The side 24 of the pocket 22 is provided with a marginal flange 35 extending the height of the side 24 to facilitate mounting the heat baffling means at the back of the stove and to strengthen and stiffen this construction about the pocket 22; the pocket 22 communicates at its bottom with a fuel reservoir 36 formed by dishing or otherwise suitably forming a plate 37 supported by a flange 38 from the bottom of the aperture 21 and secured thereto by bolt and nut assemblies 39, and supported at its opposite end or side by a strip 41 having vertical sides or legs 42 and formed to provide a supporting saddle 43 for supporting the dished plate 37, the strip 41 being secured to the frame 15 at the lower ends of the vertical members 42 by bolt and nut assemblies 44 securing flanges 45 of the strip to the frame 15.

The reservoir 36 is adapted to supply fuel through a suitable pipe connection 46 secured in the bottom of the plate 37 by jam nuts 47 arranged at opposite sides of the plate 37 to the burners of the stove, the fuel being supplied to the reservoir 36 from the tank or container 29 which is slidably positionable in the pocket 22 as will now be described.

A suitable angle or supporting bar 48 is mounted at each side of the pocket 22 by means of a face or a leg of the member 48 engaging in a horizontal slot or recess 49, as shown in Fig. 1, provided at opposite sides of the aperture 21 and secured at this end by means of a bolt and nut assembly 51 holding each supporting bar 48 to a vertical flange 52 formed in the side 14 at opposite sides of the aperture 21. The supporting bars 48 provide inclined tracks or guide members for the tank 29 and are secured at their ends opposite the aperture 21 to the vertical portions 42 of the strip 41 by means of bolt and nut assemblies 53 to provide means for sliding the tank 29 through the aperture 21 into the pocket 22 above the fuel reservoir to supply fuel to the stove.

To accomplish such sliding of the tank 29 in the pocket 22, the tank is provided with an inclined peripheral flange 54 shown more particularly in Figs. 2 and 5 having substantially the same degree of inclination as the tracks or guides 48 so that the flange 54 being aligned with the horizontal slots 49 may be inserted in the aperture 21, and the flange sliding upon the tracks or guides 48 may be pushed into the pocket until a valve stem 56 of a valve 57 slidably mounted in a threaded refilling or inlet connection or boss 58 arranged at the bottom of the tank rides upon and depresses a yielding platform or lug 59 in the reservoir 36 to lift or actuate the stem 56 whereby to supply fuel to the reservoir

from the tank. This platform or lug 59 is provided with a downwardly inclined portion 61 and a substantially horizontal portion 62 which may be slightly inclined from the horizontal for smoother engagement with and more rapid opening of the valve if so desired. The horizontal portion 62 is secured to the reservoir 37 at its front end and projects rearwardly therefrom, terminating in the downwardly inclined portion 61, which normally terminates a short distance from the bottom of the reservoir so that the member 59, being constructed of resilient metal, is capable of a certain amount of yielding or spring in its coaction with the valve stem 56. It will be manifest that this construction also permits the ready removal of the tank 29 from the pocket 22 without binding between the valve stem and the platform or lug 59 or without damaging the valve stem.

The tank 29 is adapted to close an end of the pocket communicating with the aperture 21 in order to conceal the tank within the pocket, providing means for the ready insertion or removal of the tank supported by the tracks or guides 48. To this end the tank is provided at an end thereof with a plate 63 suitably secured as by welding or soldering to the top of the tank and an angle 64 having a vertical leg 65 suitably secured to an end of the tank 29 and a substantially horizontal leg 66 projecting therefrom. The plate 63 and the horizontal leg 66 are respectively adapted to be secured by bolt and nut assemblies 67 and 68 to horizontal legs 69 and 71 of angles 72 and 73 having vertical legs suitably secured to a plate or door 74.

This plate or door 74 secured at one end of the tank 29 as already described, is provided at its top and bottom with marginal ledges or flanges 75 and 76 which seat against the side 14 above and below the aperture 21 effecting a neat closure for the aperture. A handle or finger opening 77 is formed substantially centrally of the door or plate 74 to facilitate withdrawing the tank from the pocket 22.

This door or plate 74 extends vertically above the top of the tank 29 and provides a support as shown in Fig. 5 for one end of the tank 29 when it has been removed from the pocket and inverted for the purpose of refilling or refueling the tank. The other end of the tank 29 is adapted to be supported by a handle 78 pivotally secured to the top of the tank as at 79 and adapted to swing outwardly about the pivot 79 to provide with the plate 74 a substantially level support for the tank and to facilitate carrying or transporting the tank during or after refilling it.

A feature of the present invention resides in so concealing the fuel tank 29 as above described and arranging it so that it may be readily removed from its place of conceal-

ment for the purpose of refilling or partially removed therefrom for the purpose of determining the amount of fuel contained by the tank without having to undergo the trouble of entirely removing the tank from its pocket. This feature is accomplished by so mounting the tank as to permit its ready replacement or the proper repositioning of the tank in the operating position and by sliding the tank on the tracks or guides 48 in the pocket 22 and providing the tank with a suitable fuel indicating device or gauge 81 of any usual or preferred construction near the outer end of the tank 29 so that it will be necessary to draw the tank only a comparatively short distance out of the pocket to read the gauge 81. In the present embodiment of the invention this gauge 81 is shown in Fig. 4 mounted in the top of the tank 29 adjacent the plate 63. Thus it will be understood that a fuel tank has been provided for a fluid fuel stove which is concealed within the stove body, insulated from the heat of the stove, protected against accidental injury, the tank being adapted to be positioned within the stove body by inserting it through an aperture which the tank closes, and sliding the tank along guiding tracks into an insulated pocket to the proper operating position. This construction, it will be apparent, eliminates the unsightly mounting of the tank at an end of the stove within full view as was heretofore common in the art, obviates the necessity of painstaking adjustment of the tank so that the tank valve will be in operative position, and does away with the tendency to spill fuel as the tank is removed from or replaced in operating position, thereby considerably improving the appearance and the utility of stoves employing fluid fuel for heating.

While I have illustrated a preferred embodiment of my invention many modifications may be made without departing from the spirit of the invention and I do not wish to be limited to the precise details of construction set forth but desire to avail myself of all changes within the scope of the appended claims.

Having thus described my invention, what I claim is new and desire to secure by Letters Patent in the United States is:

1. A fluid fuel stove comprising a burner portion having a plurality of burners therein, a fluid container pocket provided in said burner portion and insulated therefrom, tracks arranged at opposite sides of said pocket, and a fuel tank slidably supported by said tracks in said pocket.

2. A fluid fuel stove having an aperture in a wall thereof and comprising a burner portion, a pocket set off in said burner portion and communicating with said aperture, tracks arranged at opposite sides of said pocket, and a fuel tank having a peripheral

flange, said flange being adapted to cooperate with said tracks to support said tank within said pocket and to guide said tank through said aperture.

3. A fluid fuel stove comprising a burner portion having a pocket formed therein, a fuel reservoir communicating with said pocket, tracks arranged at opposite sides of said pocket, and a fuel tank having a peripheral flange and supported by said flange on said tracks, said tank having a valve for controlling the fuel supply contained therein.

4. A fuel tank for use in fluid fuel stoves comprising a supporting flange for supporting said tank in a stove, an outlet valve in a side of said tank, said tank being provided with a filler opening and a cover therefor, an end plate secured to said tank and extending vertically thereabove, a handle secured to said tank at a side opposite said filler opening, said handle being adapted to swing outwardly from said tank and to provide a support therefor during a refilling of the tank.

5. A fuel tank for use in fluid fuel stoves having a plate portion and a filler opening, a cap for said filler opening, a supporting member spaced from said plate portion and movably secured to said tank for movement into and out of supporting position whereby said tank may be supported for filling by said plate portion and said member.

6. A fuel tank for use in fluid fuel stoves having a plate portion and a filler opening, a cap for said filler opening, a supporting member spaced from said plate portion and movably secured to said tank for movement into and out of supporting position whereby said tank may be supported for filling by said plate portion and said member, and a valve associated with said opening and normally closing the same.

7. A fluid fuel stove having a tank receiving pocket, an inclined track, a fuel tank comprising a supporting member cooperating with said inclined track, a fuel receiving member underlying said pocket, and means to convey fuel from said receiving means.

8. In combination a fluid fuel stove having a tank receiving pocket, a fuel receiving member underlying said pocket, an inclined track, a tank having supporting means and insertable in said pocket, said track co-acting with said supporting means to guide the same, said tank being provided with a valve, and actuating means co-acting with said valve when said tank is properly positioned in said pocket.

9. In combination, a fluid fuel stove having a tank receiving pocket, a fuel receiving means, an inclined track, a tank provided with an inclined flange co-acting with said track to guide said tank to position in said pocket to deliver fuel to said receiving means.

10. In combination, a fluid fuel stove having a tank receiving pocket, a fuel receiving

- means, an inclined track, a tank provided with an inclined flange co-acting with said track to guide said tank to position in said pocket, said tank being provided with a valve, and actuating means co-acting with said valve to open the same when said tank is properly positioned in said pocket.
11. In combination, a fluid fuel stove having an apertured wall and a tank receiving pocket, a trackway leading from said aperture in said wall, fuel receiving means underlying said pocket, a tank movable through said aperture in said wall and provided with means co-acting with said trackway to support said tank in said pocket, said tank being provided with a closure plate closing the aperture in said wall when said tank is properly positioned in said pocket.
12. In combination, a fluid fuel stove having an apertured wall and a tank receiving pocket, a trackway leading from said aperture in said wall, fuel receiving means underlying said pocket, a tank movable through said aperture in said wall and provided with means co-acting with said trackway to support said tank in said pocket, said tank being provided with a closure plate closing the aperture in said wall when said tank is properly positioned in said pocket, said plate being provided with engageable means.
13. In combination a fluid fuel stove having a tank receiving recess and an entrance opening leading thereto, fuel receiving means adjacent said recess, a tank slideable into and out of said opening to and from co-operative position relative to said fuel receiving means and means to establish communication between said tank and fuel receiving means when in co-operative position.
14. In combination a fluid fuel stove having a tank receiving recess and an entrance opening leading thereto, fuel receiving means adjacent said recess, a tank slideable into and out of said opening to and from co-operative position relative to said fuel receiving means and means to automatically establish communication between said tank and fuel receiving means when in co-operative position.
15. In combination a fluid fuel stove having a tank receiving recess and an entrance opening leading thereto, fuel receiving means adjacent said recess, a tank slideable into and out of said opening to and from co-operative position relative to said fuel receiving means and means to establish communication between said tank and fuel receiving means when in co-operative position, said last named means comprising a valve in said tank and actuating means therefor operable to open said valve when in position to communicate with said fuel receiving means.

In witness whereof, I hereunto subscribe my name this 11th day of November, 1929.

WILLIAM L. COOPER.
